UNITED STATES PATENT OFFICE.

MAXIMILIAN M. SUPPES, OF ELYRIA, OHIO.

BLAST-FURNACE HEARTH.

SPECIFICATION forming part of Letters Patent No. 729,105, dated May 26, 1903.

Application filed January 22, 1903. Serial No. 140,137. (No model.)

To all whom it may concern:

Be it known that I, MAXIMILIAN M. SUPPES, of Elyria, in the county of Lorain and State of Ohio, have invented a new and useful Improvement in Blast-Furnace Hearths, of which the following is a full, clear, and exact description, reference being had to the accompanying drawings, which form a part of this specification.

10 My invention has relation to certain new and useful improvements in blast-furnaces, and more particularly to an improved construction of the hearth-jacket and iron-trough.

15 In the modern blast-furnace practice much care and attention have necessarily been given to the construction of the furnace-hearth to enable it to stand the severe conditions to which it is subjected, and various forms of 20 hearth-jackets have been devised. Some of these have promised good results and would, in fact, have proven satisfactory in service but for the fact that they have all contained one particularly weak point which has sooner 25 or later given trouble. This weak point is the point of connection between that section or portion of the jacket in which is formed the iron-tap hole and the iron-trough, through which the metal runs from the furnace in tap-

30 ping. This weakness has been due partly to the fact that the trough has been made in a separate piece held or secured to the jacket in various ways, but in every case presenting some form of a joint between the parts. This 35 joint is sooner or later found by the hot metal, which soon cuts its way therethrough, to the serious injury of the jacket and of the furnace-base. The hot metal also constantly tends to cut away the bottom of the iron

40 notch, and frequently does this to such an extent that it comes directly in contact with the jacket at and below the bottom of the trough and proceeds to cut its way out through the jacket or around the trough. Injuries to the 45 furnace caused in these ways are difficult and expensive to repair, since they require either the renewal of one or more sections of the jacket or an attempt to patch up the old sections, which is apt to be unsatisfactory by 50 leaving a weak place in the jacket.

The object of my invention is to obviate

these difficulties by providing a construction in which the weak point is entirely eliminated. This result I attain by forming the trough integrally with the section of the hearth-jacket 55 having the tap-hole therein, thereby obviating the use of any form of joint at this point. This, however, might not in all cases of itself form a satisfactory solution of the difficulty, since unless means are provided whereby the 60 trough may be effectively protected from the destructive action of the hot metal flowing through it it would soon burn out, and this would make necessary the frequent renewal of the entire jacket-section. 65

My invention therefore further consists in so constructing and arranging the trough that it is protected from destruction in a highly effective manner.

I also provide means whereby the hot metal 70 in or coming from the furnace cannot by reason of the cutting away of the bottom of the iron notch break through the jacket below the trough.

My invention also consists in the novel construction, combination, and arrangement of parts, all substantially as hereinafter described, and pointed out in the appended claims, reference being had to the accompanying drawings, in which— 75

Figure 1 is a vertical section of the lower portion of a blast-furnace embodying my invention, the section being taken through the center of the iron notch. Fig. 2 is a plan view of a portion of the furnace-hearth; Fig. 3, a 85 central vertical section through the jacket-plate and trough, and Fig. 4 is a front elevation of the same.

The letter A designates the hearth-jacket, and B the hearth-lining, of a blast-furnace, 90 which in general is of any suitable type of construction. The jacket A is built up of a number of segments or sections, which are bolted together in the usual manner. These segments or sections are preferably steel castings. In the section A' is formed the tap-hole C, and formed integrally with said section is the exteriorly-projecting iron-trough D. D' designates the refractory lining of this trough, which is continued through the tap-hole C 95 and joins the hearth-lining B. The trough and joins the hearth-lining B. The trough may be of any desired length, but is prefer-

ably in all cases long enough to extend across the water-well F at the base of the furnace, so that if any metal should escape at the joint between the trough and the runner it will not get into the well and will be far enough away from the hearth and base of the furnace to avoid any injury thereto. This also permits the trough to be surrounded by the water in the well, a feature not heretofore possible on account of the danger of metal getting out into the well. The trough is made of such depth that its bottom is considerably below the bottom of the tap-hole. This is an important feature, since it permits the lining D' to be made deep enough to extend below any point to which there is liability of the hot metal cutting its way through—that is to say, the hot metal may work its way down by cutting away the bottom of the iron notch to the lower edge of the tap-hole and may cut away the latter to a considerable distance without being able to get out through the jacket below the trough. This deep lining also protects the trough and may be permitted to cut away to a considerable extent without any danger of the trough being injured. The trough is also wide enough to permit a thick lining at the sides as well as at the bottom. The trough being thus protected interiorly by the deep lining and exteriorly by the water is rendered as durable as the jacket itself.

The water-well F may, if desired, be made to extend underneath the trough as well as at the sides thereof. This is shown in Fig. 3.

I do not limit myself to the precise construction and arrangement which I have herein shown and described, but may make such modifications therein as are fairly included in the scope of my invention as set forth in the following claims.

Having thus described my invention, what I claim as new, and desire to secure by Letters Patent, is—

45 1. In a blast-furnace hearth, a metallic hearth-jacket plate or section having a tap-hole therein, and formed with an integral iron

trough or spout into which the hot metal is discharged by the said hole.

2. In a blast-furnace hearth, a metallic 50 hearth-jacket plate or section having a tap-hole thereon, and formed with an integral iron trough or spout, and a deep refractory lining for said trough or spout extending through the tap-hole and joining the hearth-lining. 55

3. In a blast-furnace hearth, a metallic hearth-jacket plate or section having a tap-hole therein, and a trough or spout integrally joined to the plate or section and of such depth that its bottom is below the bottom of 60 the iron notch.

4. In a blast-furnace hearth, a jacket plate or section having a tap-hole and an integral trough or spout surrounding said hole, and a refractory lining for said trough of such depth 65 and thickness as to extend considerably below and laterally of the edges of said hole.

5. In a blast-furnace hearth, a water space or 70 well surrounding the hearth, a hearth-jacket plate or section having a tap-hole therein, and a trough or spout integrally joined to said plate or section and extending across the said water space or well.

6. In a blast-furnace hearth, a jacket plate or section having an integral trough adjacent 75 to the tap-hole, and a water-space adjacent to the said trough.

7. In a blast-furnace hearth, a jacket plate or section formed with a trough integral therewith and with a tap-hole which discharges 80 into said trough, and a refractory lining for the trough extending below the bottom of the tap-hole.

8. In a blast-furnace hearth, a jacket plate or section having a trough or spout formed 85 integrally therewith, a thick refractory lining for said trough, and a water-space around the exterior of the trough.

In testimony whereof I have affixed my signature in presence of two witnesses.

MAXIMILIAN M. SUPPES.
